RAZOR AND HAIR CLIPPER

George Philip Schmitt, New York, N. Y.

Application February 12, 1936, Serial No. 63,525

21 Claims. (Cl. 30—43)

This invention relates to razors and hair clippers of the power driven type.

Power driven shaving or clipping devices in vogue today usually employ a skin engaging plate or member having a series or plurality of slots forming blades between the slots and a cutter having a plurality of cutting edges, located in the rear of said slotted member. The blades of the slotted member and the cutting edges of the cutter cooperate to do the nipping or cutting of the hairs without the use of soap or a beard softener.

In this type of device the skin engaging member usually is in the form of a housing or bored member having its plurality of alternate slots and blades arranged in its skin engaging surface. The cutter is usually in the form of a member having a plurality of slots forming the cutting edges and located and operatively connected for reciprocating movement in the housing or bore of the member. Means are provided for resiliently urging the cutter against the bladed and slotted portion of the housing. A passage is provided in the cutter so that the hair after being admitted through the slots in the skin engaging member and cut by the cutter and after passing through the slots in the cutter may be collected or thrown out by the angular movements of the device during the cutting operation. The cutter unit (which includes the slotted face engaging member and the movable cutter member) is permanently fastened to the handle which carries the electric motor. The motor in these conventional devices is not self starting and requires manual effort to start the motor-shaft rotating.

The razors and hair clippers of the above-mentioned type have many features which render their use objectionable. The methods of cutting employed cause painful pulling of hairs and do not provide for a clean shearing and a smooth close clipping. Their vibration tires the hand of the user.

Because the hairs are not closely cut with present power-driven razor devices it is necessary to go over the same area so frequently that together with the constant pressure required for close contact with the area, pulling of the hairs and pinching of the skin cause an unpleasant and discomforting reaction in the user.

Power-driven razors and hair clippers of today do not effectively guide the hairs into the cutting members from any angle but require exact positioning of the razor to be effective.

Furthermore, unless the cutter is placed at substantially a right angle with relation to the skin

surface while in use, the hair guiding means usual in such razor due to faulty and inefficient construction and lack of suitable provision will cause irritation of the skin. Furthermore, they require manual effort to start the motor-shaft rotating; and no provision is made for the ready removal of the cutter unit for repair or cleaning purposes.

It is an object of this invention to provide a power-driven razor which is economical, practical, efficient and simple in construction; which obviates the aforementioned disadvantages, and by which a clean, close shave may be obtained without the use of soap or a beard softener.

It is another object of this invention to provide a razor which cuts with a shearing or scissors-like action and which cuts the hairs precisely.

It is a further object of this invention to provide a power-driven razor with means to effectively and efficiently guide the hairs to be cut into the cutter from any angle.

A still further object of this invention is to provide the shearing section of the device with guards, preferably adjustable, to permit adjustment of the cutter with relation thereto, and thus permit the desired contact with the hair or skin, and prevent irritation of the skin during manipulation of the device.

It is a further object of this invention to provide an instant and automatically starting power-driven razor.

A still further object of the invention is to provide a power-driven razor in which the driving mechanism can be removed as a unit from the device, by a mere lineal pull.

It is still a further object of this invention to provide a substantially vibrationless razor to insure easy and smooth manipulation.

This invention accordingly consists in the features of construction, combination of parts and in the unique relations of the members and in the relative proportioning and disposition thereof, all as more completely outlined herein.

To enable others skilled in the art so fully to comprehend the underlying features thereof that they may embody the same by the numerous modifications in structure and relation contemplated by this invention, drawings depicting certain forms of the invention have been annexed as a part of this disclosure, and in such drawings, like characters of reference denote corresponding parts throughout all the views, of which:

Fig. 20 is a diagrammatic view of the relative dispositions of the slots.

45 Fig. 21 is a sectional view of a modified form of cutter elements.

Fig. 22 is a side view of a portion thereof.

As an example of a device embodying the invention, let the numeral 25 generally represent the razor or clipper, the casing or housing of 50 which may be substantially rectangular in shape and may consist of a shell 26, which may be metal, a bottom 27 and top 28, which may be of suitable moulded composition. Top 28 is provided with threaded bushings 55 into which screws 55' are secured when assembling the shell 26 to the unit. Top 28 has a recess 29, into which cutter 30 is inserted. Cutter 30 may comprise two main parts, the combined hair guiding and slotted hollow stationary member or housing 60 31 having cutting edges and the longitudinally reciprocable hollow slide or cutter member 32 slidably received and guided in the hollow or slide-way of member 31. Members 31 and 32 may be substantially rectangular in shape but not necessarily so. Stationary member 31 may comprise two parts 31^a, 31^b, of which the lower part 31^b may be made of a light weight material, such as, for example, aluminum. Stationary member 31 is provided with a plurality of transverse parallelly-arranged preferably closed slots 40 through which the hair is admitted, and the lower edges of which form cutting surfaces. These slots are formed between flat surfaced blades 41 having the wedged shaped or tapered ends 42 for facilitating guiding of the hairs into slots 40. The

movable member or cutter 32 is provided with a plurality of transverse parallelly-arranged cutting preferably closed slots 39, which are disposed at an angle with respect to slots 40 as clearly shown in Figs. 5 and 8. Slots 39 are shorter in 5 length than slots 40. Arranging the slots 39 and 40 at an angle with relation to each other assures a clean shearing off of the hairs without the pulling action attendant in the use of other power-driven razors. Opening 50 in cutter member 32 10 permits the cut hair to fall through slots 39. Slots 39 provide cutting edges cooperable with blades 41 of the skin engaging stationary member 31.

The central portion R of each slot 40 in stationary member 31 is equal in length to that of an imaginary line S drawn from end to end of angular slots 39 (Fig. 5) located in sliding knife member 32, below stationary member 31. This portion R is slightly higher than the remaining 20 end portions R' of slots 40 (Figs. 3 and 8a). Each blade 41 located between adjacent slots 40 is equal in length to that of slot 40. Since blades 41 have straight top surfaces, their tapered ends 42 will project beyond portion R and above portions R' of slots 40 producing guide walls 41' forming the substantially V-shaped recesses V for guiding the hairs into slots 40. Transverse ridges G each having a curved surface are provided at both ends of the stationary cutting element 31. 30 Running longitudinally from ridge to ridge are preferably raised side-edge guards A between which and the slots 40 are the longitudinal side grooves or recesses 56. The guards A protect the skin against irritation which otherwise would result from contact of the skin with the edges and ends of the hair guiding means 41, 41', while grooves 56 permit the hairs to straighten out and thus freely be guided through recesses V into the slots 40.

The two parts 31^a and 31^b forming the stationary cutting member 31 are secured to each other by any suitable means such as two screws 43.

Located in opening 35 of bottom part 31^b are 45 two retainer balls 33, 34, the said opening being closed at both ends by cups 36, 37 having perforations for the balls 33, 34 to protrude. A tension spring 38 keeps the two balls 33, 34 spaced apart. The cutter unit 30 is thereby frictionally and 50 removably held in recess 29 of shoulder or top 26 and released by a lineal pull or movement thereof, a pin P being employed to properly locate the unit in the recess. The sliding knife member 32 is held in cutting contact with the inner surface of stationary slotted member 31 by means of pressure members which may be in the form and shape of ball-bearings, as illustrated, in which case the balls 44 are held under tension by means of a tension spring 45, which is secured in the 60 opening 46 by means of a screw or plug 47. The sliding knife member 32 is provided with a recess 48 into which extends the upper end of the reciprocating driver arm 49. This recess 48 does not cut into the central opening 50, thereby preventing any of the cut hair entering the motor compartment 51. The stationary element 30 is provided with a slot 52 longer than recess 48 and long enough to provide for the full lateral reciprocating movement of arm 49.

The electric driving motor 65 with its rotor 66 is mounted upon a U-shaped support 67 having top and bottom flanges 68, 69, respectively. Projections 70 with screw threads are provided for assembly purposes. Screws 72 secure the motor 75

support 67 to top member 28 and screws 71 secure the motor support 67 to bottom 27. When desired to take the unit apart, screws 72 are removed and the support 67 will slide out of the shell 26 with the bottom member 27, which is separated from the remainder of said support by removal of screws 71. The top and bottom members 27, 28 may be provided with ribs 73 between which the shell 26 is clamped in the assembled 10 position.

The vertical driver arm 49 rotates on pin 74 as a bearing, which pin is secured to flange 75 of support 67. The lower portion 76 of the driver arm 49 has a forked extension 77 which engages 15 the eccentric 78 connected to motor shaft 83.

Rotation of motor shaft 83 rocks driver arm 49, 76 which in turn reciprocates cutter or knife 32. Attached to plate 73' of motor 65 is an element 155 to which is secured one end of a leaf spring 20 156, the other end of which spring carries a contact point 82. The spring carries a block 158 by means of screw 157. Contact point 81 is carried by an element 159 secured to plate 73'.

Provision is made for automatic starting of 25 the motor at all times and without requiring manually operable means such as a spinning wheel heretofore used. This may be accomplished as follows: A spring 79 secured to plate 73' by screw 85 is provided with a roller 80, continuously pressing against the arm 76. The tendency of this spring mechanism is to urge arm 76 against the surface of eccentric 78, thereby returning the rotor 66 of motor 65 always to the starting position shown in Figs. 1 and 11 after 30 the power has been disconnected and maintaining it there until the power has been reestablished. In this position, the terminals 81, 82 constituting a circuit breaker for the motor are in closed contact. Rotation of motor shaft 83 will bring the second eccentric 84 carried by shaft 83 down 35 upon block 158 as shown in Fig. 12, thereby breaking contact between points 81, 82. If rotor 66 should stop in this position, the motor would not be able to start by itself, but of course, the continuously pressing roller 80 prevents this.

The motor is connected to a source of electrical power by means of the conductors C, C', C'', which are in turn connected to terminals 88, 89.

Prongs 86 pass through openings of bottom 27 50 and connect with terminals 88, 89. A condenser 87 may be mounted across the two electric terminals 88, 89 to eliminate noise transmission to external electrical devices.

The foregoing self-starting means has been described with relation to a motor having a horizontal shaft. Fig. 14 diagrammatically illustrates a self-starting means where a vertical motor shaft is used. In this case motor shaft 90 has at its upper end a driving eccentric 91. An eccentric disc 92 engages with a roller 93 mounted on a fork 94 which extends into housing 95; a tension spring 96 will always stop the rotor 97 at starting position, when contacts 98, 99 are closed, by pressing against the lowest part 65 of the eccentric 92. Housing 95 is mounted on a motor frame (not shown).

As previously stated, guards A may be employed to prevent the cutter unit irritating the skin while shaving. Relative vertical adjustment 70 between the guards and the hair guiding and entering means is desirable. Various means for this purpose may be employed, two of which are shown in the drawings. For this purpose the cutter unit may be either raised and lowered 75 with relation to the guards, or the guards may

be raised and lowered with relation to the cutter unit. Figs. 15 and 16 illustrate the adjustment of cutter unit 100 with relation to guards A''. Sloping guide slots 101, 102 are provided in which slide the fingers 103, 104 of slide members 105, 106. A spindle 107 with a knob 108 is mounted at 109; both ends 110, 111 are threaded with right hand and left hand threads. Turning the knob 108 in either direction will move the fingers 103, 104 in slots 101, 102, thereby raising or 10 lowering the cutter unit 100.

The cutter unit 120 illustrated in Figs. 17 to 19, inclusive, has a guard 121 of U formation fitting over the cutter unit.

The center portion 122 is cut out, while the 15 bridge members 123, 124 at both ends keep the unit rigidly connected. Rotatably mounted in the stationary cutting element 130 is a knob 125. Knob 125 operates an eccentric disc 126 mounted therein which raises or lowers the guard 20 121. Screw 128 threadedly mounted in element 130 and carrying knob 127 slides in slot 129. When tightened, this screw will secure guard 121 in its adjusted position. The cut away sides of the guards are turned in as at 130, 131 to 25 provide smooth surfaces.

Figs. 1 to 8 illustrate a power-driven razor in which the guards A are made integral with the cutter unit. Fig. 13 illustrates guards A' forming part of top member 28'. 30

Fig. 20 illustrates diagrammatically the relation of the slots 150 of the reciprocating cutter element to the slots 151 of the stationary cutting element. Reciprocating movement takes place between the points 150^a and 150^b. 35

The electric elements, including the motor, and other driving parts are surrounded by an insulating sleeve 152. A sleeve 153 preferably made of felt or felt composition material is interposed between sleeve 152 and the shell 26 to minimize 40 transmission of vibration.

Figs. 21, 22 illustrate the invention in a modified form. In this embodiment the face engaging cylindrical housing 165 has a longitudinal bore formed by the eccentrically arranged cylindrical wall 165' and located close to the top of the housing. Slidably arranged for reciprocative movement in opening 165' is a cylindrical cutter 166 which has an eccentric bore 167. The cutter 166 may be provided with the angular 45 transverse parallel slots 168 having cutting edges, and the housing 165 with the straight parallel transverse slots 169. Formed between slots 169 are the blades having guide extensions 170, tapered toward their ends at 171. Longitudinal 50 grooves or recesses 172 are located adjacent the extremities or ends of the slots 169.

The tapered ends 171 and grooves 172 are for guiding the hair into the hair admitting or receiving slots 169 when the housing is held close 55 to the skin during operation of the device. The extreme, raised, walls 173 of recesses 172 provide guards for the purpose hereinbefore stated. Other guards, such as those, heretofore described, may be adapted to this modified form. 65

The cutter 166 may be operatively connected for reciprocal and/or other movement with respect to housing 165 by any suitable means, such as for example, the means heretofore described with respect to the other figures. 70

It is believed from the above description that those skilled in the art will have no difficulty in understanding the construction, the method of use and operation of the device herein disclosed and a further detailed discussion thereof is un- 75

necessary. The invention is of simple and practical construction and is adapted to accomplish among others all of the objects and advantages herein set forth.

5 Without further analysis, the foregoing will so fully reveal the gist of this invention that others can by applying current knowledge readily adapt it for various applications without omitting certain features, that, from the standpoint of the 10 prior art, fairly constitute essential characteristics of the generic or specific aspects of this invention, and therefore, such adaptations should and are intended to be comprehended within the meaning and range of equivalency of the following 15 claims.

1. A shaving device comprising a member having a plurality of parallel slots with approximately parallel sides providing blades therebetween, another member below said first member 20 and having a plurality of parallel slots with approximately parallel sides providing cutting edges, the slots in one member being arranged at an angle with respect to the slots in the other member, the blades and cutting edges of the respective members cooperating for shearing hair, and means at the longitudinal edge of the first-mentioned member having an imperforate skin-engaging surface for guarding the skin against irritation during the cutting operation, and means 25 to reciprocate one member with relation to the other.

2. A shaving device comprising a member having a plurality of parallel closed slots providing blades therebetween, another member below said 30 first member and having a plurality of parallel closed slots providing cutting edges, the closed slots in one member being arranged at an angle with respect to the slots in the other member, the blades and cutting edges of the respective 35 members cooperating for shearing hair, and means at the longitudinal edge of the first-mentioned member having an imperforate skin-engaging surface for guarding the skin against irritation during the cutting operation, and means 40 to reciprocate one member with relation to the other.

3. A shaving device comprising a hollow member having a plurality of parallel slots providing blades therebetween and communicating 45 with said hollow, another member located within said hollow and having a plurality of parallel slots providing cutting edges, the slots in one member being arranged at an angle with respect to the slots in the other member, the blades and cutting edges of the respective members 50 cooperating for shearing hair, and means at the longitudinal edge of the first-mentioned member having an imperforate skin-engaging surface for guarding the skin against irritation during the cutting operation, and means to reciprocate one member with relation to the other.

4. A shaving device comprising a hollow member having a plurality of parallel slots providing blades therebetween and communicating with its 55 hollow, another hollow member located within the hollow of said former member and having a plurality of parallel slots providing cutting edges and communicating with its hollow, the slots in one member being arranged at an angle 60 with respect to the slots in the other member, the blades and cutting edges of the respective members cooperating for shearing hair and means at the longitudinal edge of the first-mentioned member having an imperforate skin- 65 engag-

itation during the cutting operation, and means to reciprocate one member with relation to the other.

5. A shaving device comprising a hollow member having a plurality of parallel closed slots providing blades therebetween and communicating with its hollow, the slots in one member being arranged at an angle with respect to the slots in the other member, the blades and cutting edges of the respective members cooperating for shearing hair, and means at the longitudinal edge of the first-mentioned member having an imperforate skin-engaging surface for guarding the skin against irritation during the cutting operation, and means to reciprocate one member with relation to the other.

6. In an article of the character described, a cutter unit comprising a slideway element having a series of parallel slots, providing blades therebetween, a slide element for said slideway and having a series of parallel slots providing cutting edges, the slots of one series being located at an angle with respect to the slots of the other series, the blades and cutting edges of the respective members cooperating for shearing hair, and guard means at the longitudinal edges of the slideway element having imperforate skin-engaging surfaces for guarding the skin against irritation during the cutting operation, and means to reciprocate one element with relation to the other.

7. In an article of the character described a cutter unit comprising a slideway having a plurality of parallel closed slots providing blades therebetween, a slide for said slideway and having a plurality of parallel closed slots providing cutting edges, the slots of said slide being located at an angle with relation to the slots of said slideway, the blades and cutting edges of the respective members cooperating for shearing hair, and guard means at the longitudinal edges of the slideway having imperforate skin-engaging surfaces for guarding the skin against irritation during the cutting operation, and means to reciprocate said slide.

8. In a device of the character described, a pair of cutter members, means for reciprocating one member relative to the other, said means including an electric motor having a rotatable part and a circuit breaker controllable by said part, and resilient means acting on said rotatable part for maintaining said part in operative position closing said breaker during the inoperative period of the device.

9. A hair cutter comprising a housing provided with a plurality of parallel closed slots, a cutter member guided in said housing and having a plurality of cutting edges, means for reciprocating said member in said housing, said housing being provided with a longitudinal groove communicating with said slots for receiving hairs for guiding into said slots.

10. A hair cutter comprising a member having a plurality of transverse slots, a cutter element having a plurality of cutting edges, means for producing relative movement of said member and element, said member being provided with a longitudinal groove communicating with ends of said slots for receiving hairs for guiding into said slots.

11. In a device of the character described

having a cutter element, a skin engaging member provided with a plurality of transverse hair admitting slots closed at an end and cooperable with said element for cutting hair, said member being provided with a longitudinal groove communicating with the closed ends of said slots for receiving hairs guided into said slots when the device is in operation.

12. In a device of the character described having a cutter element, a skin engaging member having a plurality of transverse hair admitting slots providing blades therebetween cooperable with said element, said blades having projecting ends, said member being provided with a longitudinal groove at each of said ends communicating with said slots, said ends and said groove for receiving and guiding hairs into said slots during operation of the device.

13. In a device of the character described having a cutter element, a skin engaging member having a plurality of transverse hair admitting slots providing blades therebetween cooperable with said element, said blades having projecting substantially tapered ends, said member being provided with a longitudinal groove at each of said ends communicating with said slots, said ends and said groove for receiving and guiding hairs into said slots during operation of the device.

14. In a device of the character described having a cutter element, a skin engaging member having a plurality of transverse hair admitting slots providing blades therebetween cooperable with said element, said blades having projections and the end portions of said slots being in a plane below that of their respective intermediate portions, said member being provided with longitudinal recesses communicating with the ends of said slots, said projections and recesses for receiving and guiding hairs into said slots during operation of the device.

15. In a device of the character described having a cutter element, a skin engaging member having a plurality of transverse hair admitting slots providing blades therebetween cooperable with said element, the end portions of said slots being in a plane below that of their respective intermediate portions, the longitudinal extremities of said member being above the ends of said slots providing guards and producing recesses between the guards and the ends of said blades for receiving hairs guided to said slots during operation of the device.

16. In a device of the character described having a cutter element, a skin engaging member having a plurality of transverse hair admitting slots

providing blades therebetween cooperable with said element, said member having longitudinal edges adjacent the ends of said blades raised to provide guards against irritation of the skin during operation of the device.

17. In a device of the character described having a cutter element, a skin engaging member having a plurality of hair admitting slots providing blades therebetween cooperable with said element, and means at the longitudinal edges of said member adjacent the ends of said blades and having imperforate upper edges for guarding the skin against irritation during operation of the device.

18. In a device of the character described having a cutter element, a skin engaging member having a plurality of hair admitting slots providing blades therebetween cooperable with said element, imperforate means at the longitudinal edges of said member adjacent the ends of said blades for guarding the skin against irritation during operation of the device, and means between said slots and said last means for guiding hair into said slots during operation of the device.

19. In a device of the character described having a cutter element, a skin engaging member having a plurality of hair admitting slots providing blades therebetween cooperable with said element, means at the longitudinal edges of said member adjacent the ends of said blades for guarding the skin against irritation during operation of the device, and cam means for adjusting the relative height between said last means and said member.

20. In a device of the character described, a pair of cutter members, means for reciprocating one member relative to the other, said means including an electric motor having a rotatable part, a circuit breaker controllable by said rotatable part, an eccentric connected with said rotatable part, and resilient means connected with said eccentric for automatically moving said rotatable part into position to close the circuit breaker when the motor is stopped in position for starting.

21. In a device of the character described having a cutter element, a skin engaging member having a plurality of hair admitting slots providing blades therebetween cooperable with said element, means at the longitudinal edges of said member adjacent the ends of said blades for guarding the skin against irritation during operation of the device, and wedging means for adjusting the height of the member relative to the guarding means.

GEORGE PHILIP SCHMITT.
